(57) **CLAIM**

The ornamental design for a downspout grate, as shown and described.

DESCRIPTION

FIG. 1 is a perspective view of a downspout grate, showing our new design;

FIG. 2 is a top view thereof;

FIG. 3 is a front view thereof;

FIG. 4 is a left-side view thereof;

FIG. 5 is a right-side view thereof;

FIG. 6 is a back side view thereof; and,

FIG. 7 is a bottom view thereof.

The broken lines shown in the drawings illustrate portions of the downspout grate that form no part of the claim.

1 Claim, 3 Drawing Sheets
